RUBBER IMPELLER

George G. Morse, Denver, Colo., assignor to Morse
Bros. Machinery Company, Denver, Colo., a cor-
poration of Colorado

Application April 4, 1938, Serial No. 199,909

6 Claims. (Cl. 259—103)

This invention relates to improvements in rubber impellers of the type disclosed in my Patent No. 2,115,997 dated May 3, 1938, for Impellers and lining construction, of which the 5 present application is a division.

It is now well-known that rubber and compounds thereof withstand abrasive influences better than most metal or other materials. Heretofore, rubber impeller construction has required 10 inner reinforcement of some kind as shown in the above-mentioned copending application, which discloses the use of metal and/or fabric to strengthen rubber impeller structure.

According to the present invention, an impeller for use in liquid agitation and/or aeration, especially in froth flotation operations, may be made entirely of rubber, or compounds thereof, with no added mechanical reinforcement, since rubber and its compounds when produced 20 according to the present invention will have sufficient strength and durability to satisfy the structural requirements of such use.

An object of this invention is to provide such an impeller that is made entirely of rubber, or 25 compounds of rubber, having a yielding wear-resistant surface and a relatively more rigid inner structure formed integrally therewith, thus providing a light weight and long-wearing impeller, that is well suited for use in mineral 30 pulp or the like.

A further object is the provision of an impeller of this character that requires no added mechanical reinforcement, thus saving in the time, labor and expense of producing it, as well 35 as simplifying assembly for use.

Other objects and advantages reside in details of design and construction that will be more fully disclosed in the following description and in the drawing wherein;

40 Figure 1 is a sectional view of an impeller made according to the present invention; and Figure 2 is a bottom plan view of the same.

In the drawing, reference character 5 denotes a rotary shaft, preferably hollow as at 6, on 45 which is a disk-like impeller 7 having a shaft-engaging hub 8, and vanes 9. The hub, disk and vanes are preferably made of vulcanized rubber compounds and are shown integral, which is the preferred form. The outer surfaces 50 7a of the impeller element, are made of yielding, wear-resisting rubber while the inner structure is composed of a compound of rubber that vulcanizes into a relative stiffer mass. Both compounds are vulcanized simultaneously and become an integral unit.

The advantage of forming the component parts integrally is that when the yieldable wear surface is penetrated due to excessive wear there is no peeling of this cover layer from the inner section as would occur otherwise.

The arrangement of the vanes on the lower side of the impeller disk is a copy, in the present instance, of the arrangement disclosed in the United States patent to A. J. Weinig, No. 1,998,694, issued April 23, 1935. In such an arrangement certain of the vanes are arranged substantially radial while others are arranged along chords of the circular disk 7. In use, the radial vanes impart a centrifugal component of force to surrounding liquid tending to throw 15 it outwardly, and at the same time sucking air, or any other aeration agent, down through the hollow shaft to be mixed, intimately, with the liquid. The vanes that are positioned near the periphery of the disk along chords thereof, slice 20 through the liquid and tend to draw it inwardly of the impeller. Thus intense agitation and thorough aeration are imparted to the liquid that is acted upon by the impeller, and the impeller must be rigid enough to withstand distortion.

When such liquid contains suspended solids, as in a mineral pulp in a flotation operation, the abrasive influence is present to a great degree, as the impeller rotates rapidly therein. The 30 rubber withstands the impact with the suspended solids, in an excellent manner, and, being light in weight, a minimum amount of power is required to drive the improved impeller, and wear on bearings and other associated machine parts 35 is greatly reduced.

The soft outer surfaces of the impeller resist wear and abrasion, while the inner structure gives strength, form and a degree of rigidity to the impeller while at the same time being sufficiently yieldable to permit the outer surface to exert a substantial degree of elasticity in withstanding the bombardment of abrasive particles in the material under treatment. The difference in elasticity is effected by different compounding 40 of the inner rubber and the surface rubber, prior to vulcanizing. The process of vulcanizing unites the entire mass into an inseparable unit possessing the desired properties.

The present construction also permits use of a 45 corrosion-resistant cover-layer on the impeller and whenever impellers are to be operated in materials of a corrosive nature the cover-layer may be compounded to render it especially resistant 50 55

to such corrosive action without impairing its elasticity to any appreciable degree.

It will be understood that the impeller design illustrated is merely typical of what may be used as it is within contemplation of the invention that the construction herein described may be applied to various types of impeller design as required in use.

Where the expressions "rubber" or "rubber compound" are used in the specification, they are intended to cover so-called "rubber substitutes" as well as rubber compositions.

Variations in the degree of elasticity between the inner and outer sections may be employed according to treatment requirements and changes and modifications may be availed of within the spirit and scope of the hereunto appended claims.

What I claim and desire to secure by Letters 20 Patent is:

1. As a new article of manufacture, an impeller element having means for its attachment to a rotary shaft and comprising a disk portion and integral vanes projecting from a face of the disk, 25 the impeller being composed entirely of rubber with the inner portion thereof of a composition stiffened sufficiently to withstand the stresses of normal operation without distortion, the outer wear surfaces on the stiffened portion being relatively more yielding.

2. As a new article of manufacture, an impeller element having means for its attachment to a rotary shaft and comprising a disk portion and integral vanes projecting from a face of the disk, 35 the impeller being composed entirely of rubber stiffened to a degree sufficient to withstand the stresses of normal operation without distortion, with the inner and outer portions thereof having different elastic properties.

40 3. As a new article of manufacture, an impeller element having means for its attachment to a rotary shaft and comprising a disk portion and

integral vanes projecting from a face of the disk, the impeller being composed entirely of rubber with the inner portion thereof of a composition stiffened sufficiently to withstand the stresses of normal operation without distortion, the outer 5 wear surfaces on the stiffened portion being relatively more yielding, and the inner and outer compositions being vulcanized into an integral mass.

4. As a new article of manufacture, an impeller 10 element having a hollow hub for its attachment to a rotary shaft and comprising a disk portion and integral vanes projecting from a face of the disk, the impeller being composed entirely of rubber with the inner portion thereof of a composition 15 stiffened sufficiently to withstand the stresses of normal operation without distortion, the outer wear surfaces on the stiffened portion being relatively more yielding.

5. As a new article of manufacture, an impeller 20 element having means for its attachment to a rotary shaft and comprising a disk portion and integral vanes projecting from a face of the disk, the impeller being composed entirely of rubber with the inner portion thereof of a composition 25 stiffened sufficiently to withstand the stresses of normal operation without distortion, the outer wear surfaces on the stiffened portion being relatively more yielding and of corrosion-resistant composition, and the inner and outer compositions being vulcanized into an integral mass.

6. As a new article of manufacture, an impeller element having means for its attachment to a rotary shaft and comprising a disk portion and integral vanes projecting from a face of the disk, 35 the impeller being composed entirely of rubber with the inner portion thereof of a composition stiffened sufficiently to withstand the stresses of normal operation without distortion, the outer wear surfaces on the stiffened portion being of a 40 relatively high degree of elasticity.

GEORGE G. MORSE.
